UNITED STATES PATENT OFFICE

LOUIS J. LAROCHE, OF READING, PENNSYLVANIA

DESIGN FOR A DOORSTOP OR THE LIKE

Application filed September 24, 1930. Serial No. 37,061. Term of patent 3½ years.

To all whom it may concern:

Be it known that I, LOUIS J. LAROCHE, a citizen of the United States, residing at Reading, in the county of Berks and State of Pennsylvania, have invented a new, original, and ornamental Design for Doorstop or the like, of which the following is a specification, reference being had to the accompanying drawing, forming part thereof.

Fig. 1 is a side elevation of a door stop or the like showing my new design.

Fig. 2 is a top plan view of the same.

I claim:

The ornamental design for a door stop or the like, as shown.

In testimony whereof I affix my signature.

LOUIS J. LAROCHE.
